BUILDING COVERING

Edward Roscoe Black, Chicago, Ill., assignor to
 Black Systems Inc., Chicago, Ill., a corporation
 of Illinois

Application February 25, 1930, Serial No. 431,264

6 Claims. (Cl. 108—33)

My invention relates to building coverings and is particularly concerned with flexible roofing and siding such as individual, strip shingle or roll roofing and individual, strip or roll siding.

One of the objects of my invention is to provide a new and improved building covering unit adapted to be securely fastened in place, without exposing the fastening means to view, yet allowing the unit to be free to expand and contract in response to changes in temperature, thus preventing buckling of the unit and allowing it to lie smooth under all weather conditions.

Another object of my invention is to provide a fastener adapted to be nailed to the roof or siding without penetrating the covering material.

Another object of my invention is to provide units or shingles having an under-turned portion or flap and means associated therewith for securing the units to the roof or siding without unfolding the flap during the application of the roofing.

Another object is to provide a novel and effective means for anchoring a unit, particularly the exposed or butt end thereof, to the building framework.

A further object is to provide a fastener which permits the unit associated therewith to be turned to a position to permit the fastener to be attached to the building and then to be turned to a position completely to cover the anchorage all without bending or flexing the unit.

Another object is to provide an effective, inexpensive and easily applied roof or side covering.

Still another object of my invention is to provide a method of packing covering units provided with under-turned flaps so that the units when packed for shipment will be compact packages, the flaps will be protected and the surface of each unit will not be disfigured by contact with the flaps of the adjacent units.

Other objects and advantages will be apparent from the following description and the accompanying drawings, in which

Fig. 1 is a front or top elevation of a covering unit in the form of an individual shingle made in accordance with my invention;

Fig. 2 is an enlarged vertical section taken on line 2—2 of Fig. 1;

Fig. 3 is a developed view of the shingle shown in Fig. 1;

Fig. 4 is a perspective of one form of my improved fastening clip or anchor;

Fig. 5 is a front or top elevation of a portion of a building with one form of my improved covering in place;

Fig. 6 is a perspective of a modified fastening clip or anchor;

Fig. 7 is a fragmentary rear elevation of a modified form of shingle unit and fastening clip;

Fig. 8 is a front elevation of a multiple or strip shingle unit made in accordance with my invention;

Fig. 9 is a fragmentary front view of a portion of a strip roofing or siding unit, the fastener or anchor being shown in dotted lines;

Fig. 10 is a rear view of the parts shown in Fig. 9;

Fig. 11 is an elevational view of a plurality of strip or multiple shingle units arranged in the improved manner in which they are packed for shipment;

Fig. 12 is a perspective view of the same;

Fig. 13 is a perspective view of a bundle of shingle units packed in accordance with my invention;

Fig. 14 is an elevation, similar to Fig. 11, of individual shingle units;

Fig. 15 is a perspective of the bundle shown in Fig. 14;

Fig. 16 is a perspective of a complete bundle of individual shingle units packed in accordance with my invention.

In Figs. 1 to 6 I have shown my invention as applied to individual shingle units. In Figs. 1, 2, and 3, 10 indicates a substantially square shingle having an under-turned corner flap portion 12. An aperture 14 is provided in flap 12 and the underturning forms a fold 16. This folding or underturning of the butt corner is done during the process of manufacture while the shingle unit is still hot so that no cracking takes place along fold 16 as would be the case if the bending were done after the shingle has cooled. I have provided a fastener or anchor 18 which is used to fasten the shingle unit, and particularly the exposed or butt end thereof, to the roof. The fastener is formed from a single piece of wire bent into a loop 20 and a pair of substantially straight laterally extending arms or prongs 22 which project outwardly and oppositely from the terminals of the legs of the loop or body 20 and are offset from the loop as shown at 24, the amount offset being substantially the thickness of flap 12.

In applying these roofing units, fastener 18 is first placed in position by inserting loop 20 through aperture 14 so that prongs 22 rest against the wall formed at fold 16. The fastener or anchor is then in the position shown in Fig. 1.

As will be noticed in Fig. 2, aperture 14 is lo-

cated in flap 12 so that the forward or lower edge of the opening is substantially tangent to or in the plane of the back surface of the unit body or substantially on the center of fold 16 so that the shingle may easily be swung around prongs 22 of the fastener as a door swings on a hinge.

In application to the building, the roofing unit is placed on the roof in a turned-over or inverted position as shown by shingle 26 in Fig. 5, i. e., with 10 the tip pointing downwardly. In this condition the loop of the fastener is exposed and may be fastened down to the framework in a variety of ways. I have shown a nail 28 driven through loop 20 and into the framework. Then the shingle is 15 turned over, the fastener acting like a hinge, into its proper position on the roof with the tip uppermost and the butt at the bottom and securely anchored. The tip end may be secured by nailing it down to the framework, the nails being 20 located in the region that will be covered by the overlying or next higher course of shingles.

Thus the units may be securely anchored to the roof, at the extreme butt end as well as near the tip end and yet no metal is exposed. Nor has it 25 been necessary to bend any part of the unit during its application. The clearance between the edges of the aperture in the shingle flap and the offset in the fastener (most clearly shown in Fig. 2) permits sufficient movement of the butt end 30 of the shingle to take care of all ordinary expansion and contraction under usual weather changes. Thus the butt of the shingle and the fastener or anchor are relieved of strains which are generally incident to temperature changes, 35 the fastening is rendered more reliable and the shingles are not buckled or otherwise injured.

Fig. 6 shows a modified type of fastener 27 which may be inserted into a retaining position 40 with reference to the shingle by springing the ends of the loop portion together and inserting the short prongs 29 through aperture 14, rather than by inserting the loop through the aperture as in the first described type.

In Fig. 7 I have illustrated another modified 45 type of fastener or clip 30 having a loop portion 32 and lateral prongs 34, the prongs terminating in offset hook portions 36 which are bent to point back toward the body or loop 32. To attach this 50 fastener to a shingle the fastener is sprung open and the hook portions 36 are fastened into apertures 38 in the margins of the turned-over flap. It will be noticed that this construction provides 55 the same hinge arrangement of the preferred form of fastener, and it has a further advantage in that it may be more easily and quickly applied.

Fig. 8 illustrates a twin shingle 40 provided with turned-under flaps 42 and fasteners 18 of the 60 same general construction shown in Fig. 1. This shingle is formed with vertical parallel sides 43 which greatly simplify the "laying" of roofing, due to the fact that the adjacent shingles can be readily positioned to "match up" with the shingles already in place.

In Figs. 9 and 10 I have shown a portion of a 65 roof or siding strip 44 attached to a roof or side of a building by means of a fastener 46. Strip 44 has an under-turned flap 48 provided with a plurality of apertures 50. Fastener 46 may be formed of a continuous wire and has a plurality of loops 52 formed therein and spaced apart the same distance that separates apertures 50. Loop portions 52 are offset at 54 substantially the thickness of flap 48 just as previously explained in connection 70 with the individual shingle units.

In applying this siding or roofing strip the fastener is used as a hinge in precisely the same way as previously described. The strip is swung down and out of position, the fastener properly secured to the building, and then the strip swung back into its final position on the side or roof of the building. The upper edge of the strip may be secured by suitable means, such as nails driven through the strip above the region that will be exposed; i. e., in the region covered by shingles of 10 the superposed course.

In Figs. 11, 12, and 13 I have illustrated a method of packing covering units, such, for example, as the twin shingles 40 shown in Fig. 8, provided with under-turned flaps, with the object in mind 15 of providing a package that is convenient to form and handle, will afford adequate protection for the flaps and will constitute a package of substantially uniform thickness. These results are accomplished by placing each alternate shingle so that 20 the flaps 42 are adjacent each other and the side 42a of flap 42 on the lower shingle rests against the sloping side 40a of the shingle above it. Thus adjacent shingles in the stack or bundle are offset by the amount of the flap or flaps thereof. As the 25 flaps 42 are of the same thickness as the shingles 40 it is apparent that by packing the shingles in this manner a package of uniform thickness will be produced, and no flap will lie against the face or back of any other shingle. Protecting boards 30 52 may be placed above and below the stack of shingles and suitable wires or straps secured around the package.

A similar method of packing individual shingle units is illustrated in Figs. 14, 15, and 16. A shingle 10 is placed with its flap 12 at the lower left-hand corner. A second shingle 10a is then placed on the first shingle with its flap in the upper right-hand corner and overhanging the first shingle on the right side, the width of flap 12, with the inner 40 edge of the flap resting against the edge of shingle 10. A third shingle 10b is now placed directly over shingle 10 with its flap in the upper left-hand corner and the inner edge of the flap resting against the edge of shingle 10a. A fourth shingle 45 10c is now placed directly above shingle 10a with its flap in the lower right-hand corner, the inner edge of the flap resting against the edge of shingle 10b. This procedure is repeated until a stack or bundle of the desired size is formed. 50

As shown in Fig. 14 a rectangular stack is produced and it is obvious that as many layers of shingles may be added as is desired. Boards 56 are placed below and above the stack and tying means, such as the wires 58, are fastened around 55 the package and it is ready for shipment.

Thus by employing my improved shipping package, the shingles are not marked, indented or marred by the flaps of adjacent shingles, and the flaps are protected by the overhanging 60 corners of other shingles. The package is neat, easily produced, compact and readily handled and strapped or otherwise bound to form a handy unit.

Preferably the units of my improved building 65 covering may be cut and formed from flexible prepared roofing material, such as the asphaltum impregnated and coated sheets of "felt", now in vogue. They may be covered with the usual protective coating of stone or slate. The fasteners 70 or anchors may be made of any suitable material, galvanized iron or copper wire giving good results, and ordinary roofing nails may be used to secure them in place.

Having thus described the nature and several 75

embodiments of my invention, what I claim and desire to secure by Letters Patent of the United States is as follows:

- 5 1. A building covering unit having a rigid under-turned portion, and means associated with said under-turned portion for attaching the covering unit to the building, said means adapted to be attached to the building with the covering unit in a turned-over position.
  - 10 2. A building covering unit having a body and an under-turned flap with an aperture therein, and a fastener having a loop extending through the aperture in the flap and having prongs lying within the fold between the body and flap, said 15 prongs adapted to form a bearing about which the unit may be swung to allow free access to the loop of the fastener in order to secure the same to the building.
  - 15 3. A building covering unit comprising a sheet of covering material having a body and a turned under apertured flap at one edge of the body; and an attachment for anchoring said sheet to a building framework, said attachment having a body portion lying between the flap and body of 20 the sheet to form a hinge about which the sheet may be turned at right angles to the plane of the sheet, and an extension projecting through the aperture in the flap in position to lie below the flap and be permanently secured to the building 25 framework.
  - 20 4. A building covering unit comprising a body and a turned under flap integrally formed from a sheet of covering material, the flap having an aperture therein; and an attachment for anchoring the flap to a building framework, said attachment having a body portion which lies between the flap and body of the sheet forming a hinge therefor, and an extension from the body portion, said extension projecting through the 30
  - 25
  - 30
  - 35
- aperture in the flap to hold the attachment and sheet together, said extension being exposed for attachment to a building framework when the sheet is turned down about the hinge and covered by the sheet when the same is turned up about the hinge.
- 5 6. The combination with a building covering unit comprising a substantially flat body portion, and a folded-under flap having an aperture therein adjacent the fold; of an anchoring clip 10 comprising a wire bent to form a substantially U-shaped body for attachment flat against the underlying building framework and a pair of straight arms projecting oppositely at substantially right angles to the legs constituting the 15 body, each leg of the body and its associated arm being connected by an offset portion which lies in the aperture of the covering unit so that said arms of the clip lie between the body and the flap of the unit and form therewith a hinge about 20 which the unit may be swung in a plane substantially perpendicular to the underlying frame work into position on the frame work.
6. The combination with a building covering unit comprising a substantially flat body portion, 25 and a folded-under flap having an aperture therein adjacent the fold; of an anchoring clip comprising a wire bent to form a substantially U-shaped body for attachment beneath the flap of the unit against the underlying framework and 30 a pair of straight arms projecting oppositely at substantially right angles to the legs constituting the body, said legs lying between the body and flap of the unit and forming therewith a hinge about which the unit may be swung in a 35 plane substantially perpendicular to the building frame work into position on the frame work.

EDWARD R. BLACK.
